UNITED STATES PATENT OFFICE.

GEORGE W. OTIS, OF LYNN, MASSACHUSETTS.

IMPROVEMENT IN WINDOW-VENTILATORS.

Specification forming part of Letters Patent No. 38,327, dated April 28, 1863.

To all whom it may concern:

Be it known that I, GEORGE W. OTIS, of Lynn, in the county of Essex and State of Massachusetts, have invented a new and useful Improvement in Window-Ventilators; and I hereby declare the following is a full and exact description of the same, reference being had to the annexed drawings, making part of this specification, in which—

Figure 1 is the perforated stationary plate before it is bent to the required form. Fig. 2 is a vertical transverse section, and Fig. 3 is a front view of the inside face, showing the sliding plate in a medium position, also a portion of the sash and glass.

The nature of this invention consists of a very simple and adjustable arrangement for ventilating rooms through a window thereof without subjecting the occupants to a chilling draft of air or the dampness of a rain-storm. A single piece of thin metallic plate, A, from eight to twelve inches in length by three in width, is beat longitudinally, as shown in Fig. 2, so that the upper part, c, serves as a shelter to protect the lower part from rain, and also constitutes a groove, e, for the purpose of guiding the upper edge of the sliding plate B, and the bottom constitutes two

grooves, n and u, the former of which holds and guides the bottom of the sliding plate B, and the latter embraces and rests upon the upper edge of the glass g. The upper portion of a pane of glass, g, being removed, this plate is inserted and properly secured in the place thereof, and a sliding plate, B, perforated like the stationary plate, and having a knob or handle, w, attached to the front thereof, is inserted in the grooves e and n, for the purpose of closing occasionally the apertures in the plate A. At each end of the stationary plate is a triangular piece of wood or metal, X, inserted under the shelter c for the purpose of holding the said shelter in its proper position, the upper edge of the shelter-plate being secured to the sash S.

What I claim as my invention, and desire to secure by Letters Patent, is—

A ventilating attachment to a window, consisting of the parts A, B, C, x, and w, or its equivalent, when arranged and combined with the sash and glass, all as herein shown and described.

GEORGE W. OTIS.
